VICTOR R. KOONTZ, OF WAYNESBORO, PENNSYLVANIA.

CHASER AND MOUNTING THEREFOR.

1,216,328.

Specification of Letters Patent. Patented Feb. 20, 1917.

Application filed May 21, 1915, Serial No. 29,529. Renewed January 3, 1917. Serial No. 140,469.

To all whom it may concern:

Be it known that I, VICTOR R. KOONTZ, a citizen of the United States, and a resident of Waynesboro, in the county of Franklin and State of Pennsylvania, have invented certain new and useful Improvements in Chasers and Mountings Therefor, of which the following is a specification.

My invention relates to an improvement in chasers and mountings therefor; and the primary object thereof is to provide a chaser of the type which is commonly used with rotating die heads for the purpose of cutting threads upon bolts and the like, and which can be mounted upon a die head in such a fashion that it can be readily replaced and adjusted under all conditions that are met with in actual practice.

The above and other objects and advantages of my invention will appear in the following description taken in connection with the accompanying drawings; the same characters of reference being employed to indicate the same parts throughout the several views. On said drawings:

Fig. 1 is a front view, partly in section, showing my improved chaser mounted in operative relation upon a support which is to be carried by the die head that turns the chaser;

Fig. 2 is an end view of the parts shown in Fig. 1;

Fig. 3 is a bottom plan of parts shown in Figs. 1 and 2;

Fig. 4 is a bottom plan of the holder by which the chaser is secured to the support;

Fig. 5 is a sectional view taken on line 4-4 of Fig. 4; and

Fig. 6 is a bottom plan of the chaser block.

Referring particularly to the drawings I indicate by means of the numeral 1 a support or bracket to which is secured my improved form of chaser 2; this chaser having longitudinal parallel cutting teeth 3 on one face and preferably being beveled at one end as shown at 4. The bracket or support 1 is located on the die head, which is not illustrated, in any convenient way; and it will be understood by those skilled in the art that

as many of these supports, each carrying a chaser 2, will be associated with the die head as convenience or the nature of the service to be performed dictates. It is customary for the most part to use four of these supports upon each rotating die head; the supports being of course placed equidis-

tantly apart and being located at equal distances from the center or axis of rotation of the die head. For example, in Fig. 2, the top edge of the support 1 may be conceived as having the same degree of curvature as the circular die head by which it is to be carried; and it will be seen that if each support be caused to revolve in a counter clockwise direction, the center of curvature of the beveled end 4 of each chaser 2 will describe a circle about the center of curvature or axis of rotation of the die head which will be equal to the inside diameter of the threads on the stock which the teeth 3 will cut. I may of course fix each bracket or support to the die head; or I may mount the same thereon in such a way that it can be adjusted about an axis which is parallel to the axis of rotation; whereby the chaser 2 can not only be set according to the size of the stock or bolt to be threaded, but can also be readily moved into and out of working position.

On the top of each support 1 is located an outward extending projection 5, which is shown in the form of an L-shaped rib. One side of this projection is flush with the inside edge of the support; and secured to this side is the chaser holder 6, which is in the form of an open ended trough, as particularly shown in Fig. 5. This chaser holder receives the chaser block 7, which has transverse teeth or projections 8 and the chaser block is secured to the chaser 2, which has corresponding teeth or projections 9. The teeth 9 have their forward faces, that is, their faces which are located toward the beveled end 4 of the chaser, inclined; while the rear faces of these teeth are abrupt or perpendicular to the surface in which they are formed. As for the teeth 8 on the block 7, they also have abrupt and inclined faces, but are reversely arranged; so that when the block and chaser are put together, the abrupt faces of the teeth 8 will come in contact with the abrupt faces of the teeth 9. These abrupt faces will therefore receive the longitudinal thrust against the beveled end 4 when the chaser is in operation and rearward movement of the chaser or displacement thereof away from the stock will be prevented. A bolt 10 passing through suitable slots in the projection 5, holder 6 and block 7 has its outer end threaded to engage any one of a number of screw threaded bores in the chaser 2 to retain the chaser in adjustable position, as will be presently more fully set forth.

The face of the projection 5 against which the holder 6 is secured is provided with an outward extending boss or projection 11 which fits into a correspondingly shaped recess 12 located adjacent one end of the holder 6; and the projection 11 is provided with a central screw-threaded bore to receive the end of a fastening bolt 13. The chaser block 7 has adjacent one end a short slot 14 and the holder is also provided with a hole 15 in the bottom of the recess 12; with the result that when the boss 11 is fitted into the recess 12 and the block 7 placed in the trough shaped holder 6 between the sides 16 of the same, the one bolt 13 will be sufficient to secure the block, the holder and the bracket or support 1 permanently together, as will be apparent from inspection of Fig. 1. The bolt 13 has a head on its outer end provided with a kerf to enable it to be turned by a suitable tool and this head engages a seat surrounding the slot 14; whereby the block 7 can be held in the holder and at the same time be capable of some degree 25 of sliding movement for the purpose of adjustment, as will presently appear.

The holder 7 is thickened at one end as shown at 17 and this end has a longitudinal screw threaded bore to receive an adjusting screw 18. I indicate by means of the numeral 19 the slots above mentioned in the rib 5, block 6 and holder 7; and these slots allow the bolt 10, the rib 5, the holder 6 and the block 7 to have relative movement side- 35 wise of the bolt. It will be apparent that by turning up the screw 18, this screw can be caused to engage the rear end of block 7 and force the same forward; that is to say to the left in Fig. 1. In this way the chaser 40 block 7 and the chaser 2 can be properly adjusted whenever the necessity for adjustment may arise.

The utility and mode of my invention will now be clear. In order to assemble the 45 chaser and other parts of my improvement I first secure the holder 6 and block 7 to the rib 5 by means of the screw 13, I next insert the bolt 10 through the slots 19 and cause the threaded end of the same to engage the 50 foremost one of the series of threaded holes 20 provided in the chaser 2 to receive it. This bolt has a collar thereon, which is of greater diameter than the width of the slots 19, and a polygonal head beyond the collar; so that when the bolt is turned causing the 55 threads to screw in a hole 20, the collar will engage the rib 5 along the sides of the slot therein and draw the chaser into firm contact with the chaser block and cause the 60 teeth 8 and 9 to mesh with each other. Of course the chaser 2 is adjusted longitudinally by hand before the tightening of the bolt 10 causes the teeth 8 and 9 to come together; and if any finer adjustment is necessary, it is effected by means of the screw 18

as above outlined. When the chaser 2 is adjusted by loosening the screw 10 and disengaging the teeth 8 and 9, the chaser 2 must be moved a distance that can never be less than the pitch of the teeth 8 and 9; but when adjustment within finer limits is desired the screw 18 is relied upon and by means of it the chaser 2 can be moved inward toward the stock which is being worked for any distance however minute.

Other apertures 21 may be provided where convenient to facilitate joining the above mentioned parts together or assisting in the mounting of the bracket 1 upon the die head, which is omitted from the drawings, as stated. The teeth 8 and 9 may be given any desired pitch and the diameter of the bolt 10 as well as the number of holes 20 and the spacing apart of these holes may be whatever the design of my invention and the nature of the service it is to perform may necessitate. Moreover it is not necessary that the teeth 8 and 9 be made to extend entirely across the faces of the chaser 2 and block 7; it will be sufficient if either 90 the block 7 or the chaser 2 be provided with projections and the other of these two parts be provided with corresponding recesses to receive the projections; since by such a construction practically the same results can be 95 achieved.

I wish to have it understood that the above description and drawings are illustrative only and I do not care to be limited to the exact structural details set forth, but reserve to myself the right to make whatever changes in the shape, size and arrangement of parts fairly fall within the scope and spirit of the appended claims.

Having described my invention which I 105 believe to be new I desire to secure and protect by Letters Patent of the United States:

1. A chaser having cutting teeth on one 110 face and having a plurality of threaded holes longitudinally arranged on its opposite face.

2. A chaser having cutting teeth on one face, a plurality of transversely disposed teeth on its opposite face, said teeth comprising abrupt and inclined faces, and a longitudinal row of threaded bores on said opposite face.

3. The combination of a chaser having teeth along one side and an element associated therewith, said chaser and said element having interchangeable and interengaging portions, said element being slidably mounted.

4. A chaser block having a pair of longitudinal slots and having transversely disposed teeth on one of its faces.

5. A trough shaped holder having an aperture and a longitudinally extending slot and carrying an adjusting screw adjacent one end.

6. A support for a chaser construction having a slotted projection thereon, said projection having a boss extending from one side thereof.
- 5 7. The combination of a projection with a boss extending therefrom, a holder having a recess receiving said boss, a chaser block received by said holder, the projection, the holder and the block having coinciding slots,
- 10 said block having transverse teeth on one face, a chaser having transverse teeth adapted to mesh with teeth on the block, and hav-
- ing one or more threaded bores therein, a headed bolt passing through said slots to engage one of said bores in the chaser, and 15 an adjusting screw carried by the holder to engage the block.

Signed at Waynesboro, in the State of Pennsylvania.

VICTOR R. KOONTZ.
